CLAIM

The ornamental design for a cabinet, as shown and described.

DESCRIPTION

FIG. 1 is a perspective view of a cabinet, showing our new design;

FIG. 2 is a top plan view thereof, the bottom plan view being identical thereto;

FIG. 3 is a front elevational view thereof;

FIG. 4 is a right side elevational view, the left side elevational view being the mirror image thereof; and,

FIG. 5 is a rear elevational view thereof.
